Mason C. Ames.

United States Patent Office.

MASON C. AMES, OF HARTFORD, CONNECTICUT, ASSIGNOR TO HIMSELF
AND JEREMY W. BLISS, OF SAME PLACE.

Letters Patent No. 70,987, dated November 19, 1867.

IMPROVEMENT IN JOINERS' GAUGES.

The Schedule referred to in these Letters Patent and making part of the same.

TO ALL WHOM IT MAY CONCERN:

Be it known that I, MASON C. AMES, of Hartford, county of Hartford, and State of Connecticut, have invented certain new and useful Improvement in Carpenters' Gauges; and to enable others skilled in the art to make the same, I will proceed to describe by referring to the drawings, in which the same letters indicate like parts in each of the figures.

The nature of this invention will be understood from the specification and drawings.

The object desired to be attained thereby is to produce a gauge adapted for concave and convex circles, and straight work.

Hitherto gauges have been made, having their heads perforated to receive a tooth-bar; this head being moved back and forward upon said bar, and secured at any fixed point, by means of a wood or metal thumb-screw. This style of gauge does not meet the requirements for circular work; hence this improvement. In the accompanying drawings—

Figure 1 is a side view of a gauge.

Figure 2 is an edge view of a gauge.

Letters A B C D E are detached portions of a gauge.

A is a gauge-bar, made in one or more pieces of wood, or other suitable material, and is provided with a slit, *a*, through which the clamp-screw passes, to hold the head in its proper place. One or both ends of this bar are provided with gauge-teeth *a'*. B is a gauge-head, having two straight edges *c c*; one concave shape, *d*, and one convex shape, *d'*. It is also provided with two depressions *e e'*, one at right angles with the other. These depressions are formed to receive the side of the bar A, and allow it to work closely and freely therein. Through the centre of this head is provided a hole for the reception of the clamping-bolt. C is a clamping-bolt, which is first driven into the hole of the head from the back side, so that the square portion *i* thereof will secure itself closely therein. D is a washer, which is placed on the bolt, and against the side of the bar A. E is a thumb-nut, which is fitted on to the bolt C, and the head is tightened or loosened upon the bar thereby, as desirable.

Now, it will be readily seen that when it is desirable to use a gauge on the outside or on the inside of a circle, it is only necessary to slacken the thumb-nut, so as to allow the head to be turned (a quarter turn) from its present depression *e*; thus always being in readiness to use either on straight or curved work.

I believe I have thus shown the nature, construction, and advantage of this improvement, so as to enable a person skilled in the art to make and use the same therefrom.

What I claim, therefore, and desire to secure by Letters Patent, is—

As a new improved article of manufacture, a carpenter's gauge, composed of the bar A, head B, clamp-screw C, and constructed to operate substantially as and for the purpose described.

MASON C. AMES. [L. S.]
